VALVE MECHANISM FOR ELASTIC FLUID ENGINES

Samuel Lippincott Griswold Knox, Englewood,
N. J.

Application September 18, 1937, Serial No. 164,560

14 Claims. (Cl. 121—105)

This invention relates to valve mechanisms for elastic fluid engines, and more particularly to a combined throttling, simpling and reducing valve mechanism for compound engines of the type 5 adapted to be operated ahead, stop and reverse by the continuous movement of a single operating lever.

In explanation of my invention, devices known as simpling valves have been used heretofore for changing compound engines to simple engines for the purpose of obtaining increased torque, as under starting and heavy load conditions. However, the prior simpling valves are generally of the character requiring a lever independent of the engine control for their actuation when the simpling operation is desired. The present invention contemplates a combined valve mechanism for actuation by the engine control lever, which operates in one of its functions to obtain 15 increased torque for starting and heavy load requirements, which a simpling attachment will give. With such mechanism actuatable by the single lever by which the engine is normally operated as a compound engine, the necessity of 20 providing an independent lever for the simpling operation is obviated. Thus by the proposal of the present invention the operator will actuate the lever for normal compound engine operation. If the load is more than the engine, running as a 25 compound engine, will start, the operator simply pushes his lever further along its path of movement, and such continued movement causes the valve mechanism to effect simpling and increased torque is obtained.

30 In order to discourage the use of the simpling function of the valve mechanism, except at starting or under conditions of actual necessity, the invention further contemplates a valve mechanism which is designed to admit a throttled supply of steam to the high pressure cylinder, and to the receiver during simpling operation. In this connection it will be appreciated that if steam were admitted freely through the valve mechanism, the operator would be tempted to 35 hold his lever in a position to effect simpling action of the valve in an attempt to utilize the added power for the work being done. This manner of operation would be quite detrimental to the efficiency of the engine and would make for a heavy draft on boiler capacity. By the present invention such a practice is deliberately discouraged by insuring slow-speed operation of the engine when running as a simple engine, because 40 of the throttled supply of steam to the high pressure cylinder and to the receiver. Thus the

operator will move his lever so as to restore normal compound engine operation as quickly as possible.

In order that the valve mechanism of the present invention may work in connection with the piston type reversing and distributing valve incorporated in the compound engine of my prior development without requiring any special manipulation, the invention contemplates use in the valve assembly of throttling and simpling 10 valves of the poppet type which are so related to the reversing and distributing valve that they always open in the same direction regardless of the direction that the reversing and distributing valve is moved from its central or "stop" position.

Other objects will be in part obvious and in part hereinafter pointed out in connection with the following analysis of this invention wherein is illustrated an embodiment of the invention 20 in detail.

In the drawings—

Fig. 1 is a schematic side elevation of a compound engine having associated therewith the valve mechanism of the present invention;

Fig. 1A is a partial top view of certain of the mechanism shown in Fig. 1;

Fig. 2 is an enlarged sectional view of the throttling and simpling valve of the mechanism illustrated in Fig. 1;

Fig. 3 is a part-sectional view similar to Fig. 2 illustrating in further detail the actuating means for the valve mechanism;

Fig. 4 is a partial sectional view through a compound engine of the type herein contemplated, illustrating in detail the valves controlling exhaust from the high pressure cylinder.

In the drawings, in which like reference characters designate like parts throughout the several views, there is illustrated schematically in Fig. 1 the cylinder block 5 of a compound engine, generally of the character in which the high pressure cylinder is arranged intermediate the low pressure cylinders as indicated in Fig. 4, steam from the boiler being supplied to steam line 10 connected into the valve mechanism V to be described, the steam thereupon passing to a reversing and distributing valve within the engine block as schematically indicated at 15 (Figs. 3 and 4). The reversing and distributing valve, which is preferably of the character employed with the valve gear and system of steam distribution as disclosed and claimed in my copending application Serial No. 250,623, filed January 12, 1939, is actuated to positions so as to cause 15

forward, stop and reverse movement of the engine through a link connection (not shown) with a pin 16 (Fig. 1) adapted to be rocked in either direction past its central or "stop" position by 5 the operating lever 17. Thus actuation of lever 17 in counter-clockwise direction past its mid or stop position causes movement of the distributing valve to a position causing rotation of the engine in one direction. Actuation of lever 10 17 past its mid position in the reverse direction causes the distributing valve to effect rotation of the engine in the other direction. At its mid or "stop" position, the lever 17 moves distributing valve 15 to a position cutting off admission of 15 steam to the steam cylinders.

Associated with the cylinder block 5 is a casing 6 enclosing the power take-off parts of the engine such as the cross-heads, connecting rods, crank shaft, and the like. As these parts and 20 constructions generally referred to above form no part of the present invention they will not be described in detail.

Considering now the mechanism of the present invention, reference character 20 (Figs. 2 and 3) 25 is an angled fitting forming a part of the valve casing or barrel, one leg of which is fastened to the cylinder block as at 21, and the chamber D within the fitting providing a path of flow for steam to the distributing valve 15 and thence to 30 the high pressure cylinder. The fitting 20 may be provided with an opening 22 adapted to be closed by a cap 23 secured to the fitting as by bolts 24. Transversely disposed with relation to the other leg of the fitting and journaled in the 35 fitting wall and in the cap 23 is a rock shaft 25 carrying a crank 26, adjacent the end of which is carried a roller 27. Arranged in the path of movement of the roller are the stems 30, 31 of the poppet valves 32, 33, respectively. Valve 32 40 is an auxiliary valve whose stem 30 operates in the longitudinally bored stem of the main valve 33. Valve 32 normally closes inclined ports 35 of the conically shaped main valve 33, the main valve normally closing communication between 45 the steam chamber D of fitting 20 and a chamber 38 having a restricted diameter or orifice portion 39 provided in a tubular casing part 40 welded or otherwise secured in axial relation to one leg of the fitting 20. The casing part 40 has the 50 steam inlet connection 10 secured thereto for supplying the chamber 38 with steam at boiler pressure. With the parts so far described it will be seen that as shaft 25 is rocked roller 27 first lifts the auxiliary poppet valve 32 a very small 55 amount. Then the roller 27 comes against the spindle or stem 31 of the main poppet throttle valve 33, with continued movement of the roller 27 lifting valves 32 and 33. The purpose of the small valve 32 is to permit a partial admission of 60 steam to the engine without the hand feeling too much resistance and thus tending to open the valve jerkily. As valves 32 and 33 are lifted, steam passes from line 10 and chamber 38 to the chamber D of the fitting 20 and thence to the 65 high pressure cylinder of the engine, through the distributing valve and cylinder operating valve.

Valves 32, 33 are normally seated by the action of a coil spring 45, one end of which engages against a spring seat 46 rockably seating against 70 valve 32, the other end reacting against an end of a tubular casing member 47 which is arranged axially with reference to the casing part 40 and secured thereto as by bolts 48. These bolts extend through an end cap 50 and also serve to 75 secure between the end cap and the adjacent end

of fitting 47 the casing part 51 to be described, the bolts being threaded into the end flange provided on the part 48.

The closed end of the casing part 47 is elongated to provide a hub 53 extending into the 5 related end of the chamber 38, the hub receiving the stem 54 of a poppet valve 56 normally closing off communication between chamber 38 and chamber 57 formed within the casing part 47 through communicating passages 58. 10

Valve 56 is subjected to the pressure of steam in chamber 38 and, opening away from this chamber, would be lifted by the steam pressure were it not held down by the pressure of a spring 60 engaging against the valve 56. Spring 60 is 15 made sufficiently powerful to hold valve 56 closed against full boiler pressure. However, continued rotation of rock shaft 25 causes roller 27 to lift valves 32, 33 until spring seat 46 engages against stem 54 of valve 56, thus forcing valve 56 to open 20 against the pressure of spring 60. Steam from line 10 is thereupon admitted to chamber 57.

The casing part 51 is provided with ports 62 which connect the chamber 57 with a chamber 63 formed in the end cap 50. Part 51 is further provided with a chamber 64, communication between chambers 63 and 64 being established upon lifting of a valve 65 whose stem extends into and engages against the end of a floating spring cage 66 against which one end of spring 60 reacts. 25 Valve 65, which will hereinafter be referred to as a "simpling valve," thus controls communication between chambers 63 and 64, the latter communicating with the receiver space through a connection 70 (see Fig. 4). 30

Upon steam being admitted to chamber 57 due to lifting of valve 56, steam is also admitted to chamber 63 through ports 62 and causes the simpling valve 65 to open against the action of spring 60, thus admitting steam to the receiver 40 through chambers 63, 64 and connection 70. Steam pressure in the receiver now builds up to a predetermined value at which back pressure in the chamber 64, combined with the pressure of spring 60 acting on the stem of valve 65 through 45 the floating cage 66, causes valve 65 to close. In the preferred arrangement the area of valve 65 and the pressure of spring 60 are so proportioned that valve 65 will close at a predetermined point, for example, one-half full boiler pressure, despite 50 the full boiler pressure on top of it. It is obvious, however, that if it is desired to admit steam at boiler pressure to the receiver the spring 60 could be omitted or left loose, or other arrangements provided to pass steam direct from line 10 55 or chamber 38 to the receiver.

Connection 70 to the receiver is provided with a T 71, from which a line 72 extends to a small cylinder 75 arranged in the exhaust space and placed generally under the middle of the high 60 pressure cylinder. A check valve 74 is provided in line 70 between the receiver and the T 71 to prevent steam from the receiver going to cylinder 75 during normal operation of the engine. Within the cylinder 75 is arranged a plunger 76 urged to its down position by a spring 77 and connected through a stem 78 with an upwardly opening poppet valve 80 which opens and closes the chamber 81 to the lower exhaust ports 82 of the high pressure cylinder. 65

Arranged on the upper side of the high pressure cylinder is a chamber 83 into which open the upper exhaust ports 84 of the high pressure cylinder. Communication between the upper chamber 83 and the receiver space is established 70 75

by an upwardly opening poppet valve 85 urged to closed position by spring 86.

Steam exhausting from the high pressure cylinder into the chamber 83 through the exhaust ports 84, as occurs during normal compound engine operation, acts to overcome the force of spring 86, and thus lifts the upwardly opening poppet valve 85, allowing steam to pass directly from the high pressure cylinder into the receiver 10 subsequent expansion into the lower pressure cylinders. When, however, the valve 80 is lifted by steam being supplied to the cylinder 75 upon opening of the simpling valve 65, steam exhausts from the high pressure cylinder and chamber 81 directly into the low pressure exhaust chamber and thence to condenser or atmosphere. Due to the fact that steam at relatively high pressure is admitted to the receiver space upon opening of the simpling valve 65, valve 85 has this relatively high receiver pressure on top of it and will therefore remain closed while the exhaust from the high pressure cylinder passes directly out of the engine. The low pressure cylinders may simultaneously take the steam from the receiver and exhaust the engine as usual.

By the above described arrangement it will be seen that lifting of valves 32, 33 in the manner described first admits steam direct to the high pressure cylinder and only to the high pressure cylinder. When this is done, the engine acts as a normal compound engine. Further movement of the valves 32, 33 thereupon acts to throttle the flow of steam from steam line 10 to the chamber D and thence to the high pressure cylinder, due to the fact that the continued lifting of valves 32, 33 causes spring seat to move into the restricted diameter portion 39 of the chamber 38. After this throttling takes place, the simpling valve 65 is opened, thereby admitting higher pressure steam from the boiler direct to the receiver space than the receiver would get in normal operation as a compound engine. Simultaneously therewith, through steam being supplied through connection 72 to cylinder 75 to open valve 80, steam from the high pressure cylinder is allowed to exhaust directly from the engine instead of into the receiver space.

The purpose of the choking or throttling action of the element 46 in its relatively raised position is to provide, when the flow of steam into the receiver space upon closing of the simpling valve is reduced for the reasons above explained, that the flow of steam into the high pressure cylinder direct from the boiler through valves 32, 33 will also be throttled. Otherwise, with the high pressure cylinder getting steam at full boiler pressure, and with the valves 32 and 33 in their full open position before any throttling action is effected, the performance of the engine would be jerky, with the high pressure cylinder getting its maximum supply of boiler steam and exhausting directly to the atmosphere, while the low pressure cylinders would be getting the much reduced quantity coming from the simpling and reducing valve to the receiver space.

While the steam pressure reducing action is as described above in the valve mechanism illustrated, it is of course understood that other types of steam pressure reducing action may be incorporated such as the well known types in which the steam pressure from the boiler is reduced only when the boiler pressure exceeds the pre-determined maximum pressure to be admitted to

the receiver, or in which a constant ratio is maintained between the boiler pressure and the reduced pressure admitted to the receiver.

Referring to Figs. 3 and 4, wherein is shown the valve mechanism operating means, it has been previously pointed out that when the lever 17 is actuated in one direction the distributing valve 15 is moved to a position causing the engine to rotate in one direction and when moved in the reverse direction actuates the distributing valve to a position causing rotation of the engine in the other direction. To permit of a single operating lever by which the throttling and simpling valves aforesaid may be actuated at or near the end of the forward and reverse strokes of the lever, whereby the operator may simply push his lever further along its path of movement to effect simpling action regardless of direction of rotation of the engine as a compound engine, there are provided the connections between the lever 17 and the rock shaft 25, as follows:

Rock shaft 25 has secured to it as by pin connection the crank arm 90, the free end of which is provided with a stud carrying angularly related rod sockets 91a and 91b. Threaded into the socket members so that their axes converge are the rods 92, 93. Rod 92 extends through a pivoted socket member 94 carried by the lever and arranged relatively above the axis of pin 30 16 on which lever turns. Rod 93 similarly extends through a pivoted socket member 95 carried by the lever relatively below the axis of the lever fulcrum pin 16. The ends of each of the rods 92, 93 are threaded and are each provided with a stop nut 96 with which may be associated a lock nut 97.

In operation, and assuming that lever 17 has been actuated in either direction to take up the lost motion provided to permit the reversing and distributing valve to be moved well over into a definite forward or reverse position before steam gets past the valves 32, 33, further movement of lever 17 in that direction causes a stop 96 to engage either one of the sockets 94, 95 depending on the direction of throw of the lever, and shaft 25 is rotated to lift valves 32, 33 and thus admit steam from line 10 to chamber D and thence to the high pressure cylinder. The engine now operates as a compound engine and continues to so operate up to the point where valves 32, 33 engage the stem 54. Further movement of the lever 17 in the direction to which it has been actuated changes the engine from compound to simple, as valves 32, 33 lift stem 54 55 and open the simpling valve 65 as described.

It is to be here noted that axial movement of either rod 92, 93 results in turning movement of crank arm 90 and rocking movement of the rock shaft 25 always in the same direction. Uniform directional rocking movement of the shaft 25 thus results in opening movement of the poppet valves 32, 33 and simpling valve 65 in the same direction, regardless of whether simpling is effected near the end of either the forward or reverse operations of the engine.

In addition to the above operation, which relates generally to conditions of unusual load, the valve mechanism of the present invention has the added function of providing means for starting the engine following a time period during which the engine has stood still or has coasted, with the result that little or no steam remains in the receiver. If the high pressure piston is then between its cut off position and the end of 75

its stroke, or if it is at or near dead center, so that normal opening of the valve 33 does not start the engine, the lever 17 can be further actuated so as to cause the simpling valve to admit steam to the receiver which in turn is admitted to the low pressure cylinder or cylinders to actuate whichever of the pistons thereof is in a position to start the engine. Thus direct admission of steam to the receiver upon the described operation of the lever 17 assures starting of the engine from all positions.

As many changes could be made in carrying out the above constructions, without departing from the scope of the invention, it is intended that all matter contained in the above description or shown in the accompanying drawings shall be interpreted as illustrative and not in a limiting sense.

I claim:

20. 1. In a mechanism for simpling a compound engine incorporating a high pressure cylinder, a receiver space, at least one low pressure cylinder receiving steam from the receiver space, and an exhaust space, the combination of a lever movable to a position in which it effects admission of steam to the engine for normal compound operation, during which operation the high pressure cylinder exhausts into the receiver space, means responsive to actuation of the lever beyond that position to effect continued admission of steam to the high pressure cylinder, and also to effect admission of steam direct to the receiver at a relatively higher pressure than would result from normal compound operation, and exhaust control mechanism including means responsive to the relatively high receiver pressure to cause the high pressure cylinder to exhaust directly into the exhaust space.

2. In mechanism for throttling and simpling a compound engine incorporating a high pressure cylinder, a receiver space, at least one low pressure cylinder receiving steam from the receiver space, and an exhaust space, the combination of a lever movable to a position in which it effects admission of steam to the engine for normal compound operation, during which operation the high pressure cylinder exhausts into the receiver space, means responsive to actuation of the lever beyond that position to effect throttling of the steam being admitted to the high pressure cylinder, and also to effect admission of steam direct to the receiver at a relatively higher pressure than would result from normal compound operation, and exhaust control mechanism including means responsive to the relatively high receiver pressure to cause the high pressure cylinder to exhaust directly into the exhaust space.

3. In mechanism for throttling and simpling a compound engine incorporating a high pressure cylinder, a receiver space, at least one low pressure cylinder receiving steam from the receiver space, and an exhaust space, the combination of a lever movable to a position in which it effects admission of steam to the engine for normal compound operation, during which operation the high pressure cylinder exhausts into the receiver space, a throttling and simpling valve mechanism responsive for actuation to the actuation of the lever beyond that position first to effect throttling of the steam being admitted to the high pressure cylinder and thereafter to admit steam direct to the receiver at a relatively higher pressure than would result from normal compound operation, and exhaust control mechanism including means responsive to the relatively high receiver

pressure to cause the high pressure cylinder to exhaust directly into the exhaust space.

4. In mechanism for throttling and simpling a compound engine incorporating a high pressure cylinder, a receiver space, at least one low pressure cylinder receiving steam from the receiver space, and an exhaust space, the combination of a lever movable to a position in which it effects admission of steam to the engine for normal compound operation, during which operation the high pressure cylinder exhausts into the receiver space, means responsive to the actuation of the lever beyond that position first to effect throttling of the steam being admitted to the high pressure cylinder, means also responsive to the actuation of the lever beyond the position aforesaid thereafter to effect admission of steam direct to the receiver at a relatively higher pressure than would result from normal compound operation, and exhaust control mechanism including means responsive to the relatively high receiver pressure to cause the high pressure cylinder to exhaust directly into the exhaust space.

5. In mechanism for throttling and simpling a reversing compound engine incorporating a high pressure cylinder, a receiver space, at least one low pressure cylinder receiving steam from the receiver space, and an exhaust space, the combination of a lever movable from a mid-position to forward and reverse positions in which it effects forward and reverse rotation of the engine operating as a compound engine, during which operation the high pressure cylinder exhausts into the receiver space, mechanism including unidirectionally operable throttling and simpling valves each responsive for actuation to the actuation of the lever beyond the forward and reverse positions aforesaid to effect throttling of the steam being admitted to the high pressure cylinder and to admit steam direct to the receiver at a relatively higher pressure than would result from normal compound operation, and exhaust control mechanism including means responsive to the relatively high receiver pressure to cause said high pressure cylinder to exhaust directly into the exhaust space.

6. In mechanism for throttling and simpling a reversing compound engine incorporating a high pressure cylinder, a receiver space, at least one low pressure cylinder receiving steam from the receiver space, and an exhaust space, the combination of a lever movable from a mid-position to forward and reverse positions in which it effects forward and reverse rotation of the engine operating as a compound engine, during which operation the high pressure cylinder exhausts into the receiver space, means unidirectionally responsive to actuation of the lever beyond the forward and reverse positions aforesaid to effect throttling of the steam being admitted to the high pressure cylinder and to effect admission of steam direct to the receiver at a relatively higher pressure than would result from normal compound operation, and exhaust control mechanism including means responsive to the relatively high receiver pressure to cause the high pressure cylinder to exhaust directly into the exhaust space.

7. In mechanism for throttling and simpling a reversing compound engine incorporating a high pressure cylinder, a receiver space, at least one low pressure cylinder receiving steam from the receiver space, and an exhaust space, the

- combination of a lever movable from a mid-position to forward and reverse positions in which it effects forward and reverse rotation of the engine operating as a compound engine, during which operation the high pressure cylinder exhausts into the receiver space, means unidirectionally responsive to actuation of the lever beyond the forward and reverse positions aforesaid to effect throttling of the steam being admitted to the high pressure cylinder, means also unidirectionally responsive to actuation of the lever beyond the forward and reverse positions aforesaid to effect admission of steam direct to the receiver at a higher pressure than would result from normal compound operation, and exhaust control mechanism including means responsive to the relatively high receiver pressure to cause the high pressure cylinder to exhaust directly into the exhaust space.
8. In apparatus of the character described, the combination of a steam engine incorporating a high pressure cylinder, a receiver space, the high pressure cylinder normally exhausting into the receiver space, at least one low pressure cylinder receiving its steam from the receiver space, and an exhaust space, a steam line to the engine, valve means in said line for controlling admission of steam to the high pressure cylinder, valve means in said line for controlling admission of steam direct to the receiver, mechanism responsive to the receiver pressure following actuation of the second valve means and including means responsive to the relatively high receiver pressure to cause the high pressure cylinder to exhaust directly to the exhaust space, and means for actuating both said valve means.
9. In apparatus of the character described, the combination of a steam engine incorporating a high pressure cylinder, a receiver space, the high pressure cylinder normally exhausting into the receiver space, at least one low pressure cylinder receiving its steam from the receiver space, and an exhaust space, a steam line to the engine, valve means in said line for controlling admission of steam to the high pressure cylinder, valve means in the line actuatable upon a predetermined actuation of the first valve means for controlling admission of steam direct to the receiver, and mechanism responsive to the actuation of the second valve means and including means responsive to the relatively high receiver pressure to cause the high pressure cylinder to exhaust directly into the exhaust space, and means for actuating the first valve means.
10. In apparatus of the character described, the combination of a steam engine incorporating a high pressure cylinder, a receiver space, the high pressure cylinder normally exhausting into the receiver space, at least one low pressure cylinder receiving its steam from the receiver space, and an exhaust space, a steam line to the engine, valve means in said line for controlling admission of steam to the high pressure cylinder, means for throttling steam admitted to the high pressure cylinder under the control of the valve means, simpling valve means for controlling admission of steam direct from the line to the receiver, the throttling means and the simpling means being actuatable upon a predetermined actuation of the first valve means, mechanism responsive to the actuation of the second valve means and including means responsive to the relatively high receiver pressure to cause the high pressure cylinder to exhaust directly into

the exhaust space, and means for actuating the first valve means.

11. In apparatus of the character described, the combination of a steam engine incorporating a high pressure cylinder, a receiver space, the high pressure cylinder normally exhausting into the receiver space, at least one low pressure cylinder receiving its steam from the receiver space, and an exhaust space, a steam line to the engine, valve means in said line for controlling admission of steam to the high pressure cylinder, means for throttling steam admitted to the high pressure cylinder under the control of the valve means, simpling valve means operative to admit steam direct from said line to the receiver at a pressure lower than the line pressure but higher than that resulting from normal compound operation, the throttling means and the simpling means being actuatable upon a predetermined actuation of the first valve means, mechanism responsive to the actuation of said simpling means and including means responsive to the relatively high receiver pressure to cause the high pressure cylinder to exhaust directly into the exhaust space, and means for actuating the first valve means.

12. In apparatus of the character described, the combination of a steam engine incorporating a high pressure cylinder, a receiver space, the high pressure cylinder normally exhausting into the receiver space, at least one low pressure cylinder receiving its steam from the receiver space, and an exhaust space, a steam line to the engine, a poppet-type control valve in said line for controlling admission of steam to the high pressure cylinder, spring means normally closing said valve, means for lifting said valve, a simpling valve operatively connected in the line and controlling the passage of steam from the line direct to the receiver, said simpling valve being responsive for its actuation to the pressure of steam from the line, means operative upon a predetermined lifting of the control valve to admit steam to the simpling valve and thence at relatively high pressure to the receiver, and mechanism responsive to actuation of the simpling valve and including means responsive to the relatively high receiver pressure to cause the high pressure cylinder to exhaust directly into the exhaust space.

13. In apparatus of the character described, the combination of a steam engine incorporating a high pressure cylinder, a receiver space, the high pressure cylinder normally exhausting into the receiver space, at least one low pressure cylinder receiving its steam from the receiver space, and an exhaust space, a steam line to the engine, a poppet-type control valve in said line for controlling admission of steam to the high pressure cylinder, spring means normally closing said valve, means for lifting said valve, a simpling valve operatively connected in the line and controlling the passage of steam from the line direct to the receiver, spring means normally maintaining the simpling valve in one position, and the simpling valve moving against said spring means in response to the pressure of steam from the line, a poppet-type valve controlling admission of steam from the line to the simpling valve, spring means normally closing the last-named valve, and the last-named valve lifting upon a predetermined lifting of the control valve whereby to admit steam to the simpling valve and thence at relatively high

pressure to the receiver, and mechanism responsive to actuation of the simpling valve and including means responsive to the relatively high receiver pressure to cause the high pressure cylinder to exhaust directly into the exhaust space.

14. In apparatus of the character described, the combination of a steam engine incorporating a high pressure cylinder, a receiver space, the high pressure cylinder normally exhausting into the receiver space, at least one low pressure cylinder receiving its steam from the receiver space, and an exhaust space, a steam line to the engine, a poppet-type control valve in said line for controlling admission of steam to the high pressure cylinder, spring means normally closing said valve, means for lifting said valve, a simpling valve operatively connected in the line and controlling the passage of steam from the line direct to the receiver, spring means

normally maintaining the simpling valve in one position, and the simpling valve moving against said spring means in response to the pressure of steam from the line, means operative upon a predetermined lifting of the control valve to throttle the admission of steam to the high pressure cylinder, a poppet-type valve controlling admission of steam from the line to the simpling valve, spring means normally closing the last-named valve, and the last-named valve lifting upon a further predetermined lifting of the control valve whereby to admit steam to the simpling valve and thence at relatively high pressure to the receiver, and mechanism responsive to actuation of the simpling valve and including means responsive to the relatively high receiver pressure to cause the high pressure cylinder to exhaust directly into the exhaust space. 5 10 15 20

SAMUEL LIPPINCOTT GRISWOLD KNOX. 20
